UNITED STATES PATENT OFFICE.

EDWIN A. JEFFERY, OF BOSTON, MASSACHUSETTS, ASSIGNOR OF ONE-HALF
TO HOUGHTON & DUTTON, OF SAME PLACE.

EASEL.

SPECIFICATION forming part of Letters Patent No. 425,177, dated April 8, 1890.

Application filed August 29, 1889. Serial No. 321,370. (No model.)

To all whom it may concern:

Be it known that I, EDWIN A. JEFFERY, of Boston, county of Suffolk, State of Massachusetts, have invented an Improvement in Easels, 5 of which the following description, in connection with the accompanying drawings, is a specification, like letters and figures on the drawings representing like parts.

My invention therefore consists in the combination, with the side rails and cross-bars of an easel, of parallel supporting-bars rigidly attached to said cross-bars and provided each with a series of independent supports or hangers, and a rest having hooks to engage said 15 supports or hangers, substantially as will be described.

Figure 1 shows in perspective an easel embodying this invention. Fig. 2 shows a vertical section of one of the supporting-bars for 20 the rest on a larger scale, and Fig. 3 a modification to be referred to.

The side rails *a* and cross-bars *b* are of usual or suitable construction. The rest *c* is provided with two or more hooks *c'* at or near 25 its ends. Supporting-bars *d* are secured to the cross-bars *b* and arranged parallel with each

other, being slotted longitudinally, as at *d'*, and provided at intervals throughout their length with pins *2* or other independent supports or hangers. The hooks *c'* of the rest *c* 30 are adapted to engage the pins *2*.

It will be seen that the rest *c* may be readily detached and applied to any one of the series of supports or hangers *2*.

I claim—

In an easel, the side rails and cross-bars *b*, combined with parallel supporting-bars *d*, slotted longitudinally at *d'* and rigidly attached to said cross-bars, and provided each with a series of independent supports or hangers 40 extended at intervals across said slots, and the rest *c*, having hooks *c'* projecting from its rear side to enter said slots and engage said supports or hangers, substantially as described. 45

In testimony whereof I have signed my name to this specification in the presence of two subscribing witnesses.

EDWIN A. JEFFERY.
